UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

CONNECTION MECHANISM.

Application filed February 6, 1922. Serial No. 534,536.

To all whom it may concern:

Be it known that I, RICHARD LESTER WILCOX, a citizen of the United States, residing at Waterbury, in the county of New Haven and State of Connecticut, have invented certain new and useful Improvements in Connection Mechanisms, of which the following is a specification, reference being had therein to the accompanying drawings.

10 This invention relates to connection mechanisms and refers more particularly to means for connecting a power member with an operated member that will so yield when subjected to excessive strains that thereafter 15 one of the members will remain stationary.

Among the aims and objects of this invention, among other things, may be recited the provision of a device of the character mentioned with a view to compactness in which 20 the number of parts are few, the construction simple, cost of production small and efficiency of operation high.

These and other objects I obtain by means of such construction and relative arrangement of parts as will be apparent from an inspection of the accompanying drawings in connection with the description herein-after contained and wherein a preferred embodiment of the invention is disclosed for 25 the purpose of imparting an understanding of the same.

In the drawings wherein like characters of reference indicate corresponding parts in the several figures;

30 Figure 1 is a side elevation of my improved connection mechanism as applied to a heading or upsetting machine, the parts being in the relative position occupied by them while operating under the normal conditions;

Figure 2 is a similar view showing the relative position of the parts after the fragile element has been broken, as a result of an abnormal operating strain;

35 Figure 3 is a sectional view of the parts, taken generally upon line 3—3 of Figure 1;

Figure 4 is a perspective view of the arm member; and

Figure 5 is a similar view of the shearing member.

My improved device is adapted for use with many forms of mechanisms, but for the purpose of illustration I have shown the same as associated with the mechanism for operating the plunger of a heading or up-

setting machine of the type substantially 55 as shown in the patent to R. L. Wilcox, No. 1,104,090 dated July 21, 1914.

In the drawings, 10 designates the body of a heading machine, 11 the plunger that has a reciprocatory movement thereon, 12 60 the rock lever journaled upon a stud 13 in said body and carrying a cam roll 14 which is held in contact with a cam 15 from which motion is imparted to the rock lever.

The parts above described are common 65 and well known in the art and require no further description herein.

My improved device consists in the means for connecting the rock lever 12 with the plunger 11 whereby a reciprocatory movement is transmitted to the latter from the former.

One preferred form of said mechanism consists of an arm member 16 connected with the rock lever 12 by the stud 17 and having 75 a head 18 through which is a recess 19 at substantially a right angle to the axis of the stud 17; and a shearing member 20 which is pivotally connected with the plunger 11 by the stud 21 and having a recess 22 80 therein which lies substantially parallel with the axis of the stud 21.

The arm member 16 and shearing member 20 are pivotally secured together by the stud 23 having a head 24 at one end and a 85 nut 25 on the opposite end. Other means for connecting these members may be utilized, however, and my invention is not therefore limited to the exact means herein shown.

90 The shearing bar 26 is preferably rectangular in cross-section with a plurality of notches 27 in opposite faces thereof substantially opposite each other. By reason of these notched faces, the shearing bar is formed into a plurality of sections 28. This bar is inserted within the recess 19 with the innermost section 28 projecting beyond the lower face 29 of the head 18, as shown in Figure 1, with the bottoms of two of the notches 27 in substantial alignment with said face. It is thus held rigidly by a clamp 30 which is adjustably secured by the screws 31 and 32 in a well known manner, these latter being threaded through the head portion 18 and the former having nuts 33 thereon to hold the same against endwise movement.

100 In Figures 1 and 3 my mechanism is

- shown with the parts assembled and providing a positive connection between the rock lever 12 and the plunger 11, at which time the wall 34 of the recess 22 is in contact with 5 one side of the projecting section 28, see Figure 1, and the face 35 thereon is in contact with the face 36 of the arm member, thus making a rigid connection with the parts locked against relative movement.
- 10 With all of the mechanism operating under normal strain, the strength of the shearing bar 26 is sufficient to transmit the motion of the rock lever 12 to the plunger 11. If movement of the plunger is interfered 15 with, however, by excessive strain, the continued movement of the rock lever 12 actuates the arm member 16 and shearing member 20 relatively to each other in very much the same manner as a toggle, about the axis 20 of the stud 23 until they occupy the positions substantially as shown in Figure 2.

During this action the shearing member 20 breaks off the projecting section 28 of the shearing bar 26 against the clamp 30. The 25 rock lever will thereafter continue its movement without transmitting motion to the plunger 11, the arm member 16 and shearing member 20 moving relatively upon the stud 23.

- 30 The mechanism is restored for transmitting motion by advancing the shearing bar 26 so that the next succeeding section 28 will project beyond the face 29 of the arm member 16 as before, manipulation of the 35 clamp 30 permitting this to be done.

The sections 28 are each successively broken from the shearing bar 26 at the weakest point, that is, between the notches 27 so that only a small portion of the bar is lost 40 at each shearing action.

In order to prevent the section 28, broken off from the shearing bar 26, from flying wild and thus possibly cause injury, I have provided means for controlling its movement. This comprises a member 37 preferably integral with the shearing member 20, having an opening 38 therethrough in part forming an extension of the recess 22, having a downwardly flaring floor 39 and 45 an enclosing hood 40 at the top thereof.

The shearing bar 26 occupies a generally vertical position with the lower section 28 projecting into the recess 22 and as it is broken off in the manner above described, 50 it falls by gravity onto the inclined floor 39 being held against lateral movement by the walls of the member 37 and from flying upwardly by the hood 40. Thus the section as broken off is prevented from moving except in a defined path and drops from the inclined floor 39 into a receptacle conveniently arranged to receive it, if so desired.

An inclined face 41 upon the head 18 of the arm member 16 provides an additional safeguard against the broken off section fly-

ing inwardly and insures its controlled movement during that portion of the rotary movement of the shearing bar 20 immediately after the section has been broken off.

As the bottom portions of the notches 27 70 are inside of the face 29, the lowermost section 28 is so broken off that any projecting or ragged edge is inside of said face 29. Therefore no projecting or ragged edge can interfere with the operation of the shearing 75 member.

Obviously minor changes and alterations may be made within my invention aside from those herein suggested, and I desire it to be understood that I do not limit myself 80 to the exact construction herein shown and described, but claim all that falls fairly within the spirit and scope of the appended claims.

What I claim as new and desire to secure 85 by Letters Patent, is:

1. In connection mechanism, companion members operatively connected with each other, and a shearing element secured in one member, a part thereof extending beyond 90 said member and into the path of movement of the other member, so that when the said members are moved in relation to each other that part of the shearing element extending beyond the member to which it is 95 secured is broken off.

2. In a connection mechanism, companion members operatively connected with each other, and a shearing element secured in one member and projecting into the path of the 100 other member so that when the same are moved in relation to each other, a portion of said shearing element is broken off, and means for guiding the movement of the said broken off portion.

3. In a connection mechanism, an arm member, a shearing element formed into sections separated by weakened portions, means for securing said shearing element in said arm member so that one of the sections will project beyond a face thereon, with a weakened portion thereof registering therewith; means for operatively connecting said members together whereby a portion of said shearing element is held in contact with the 110 projecting section of said shearing element, and means for controlling the movement of that portion of the shearing element separated therefrom.

4. In a connection mechanism, companion 120 members, one an arm member and the other a shearing member, operatively connected with each other; a shearing element having a section at one end separated from the other part thereof by a weakened portion; movable 125 means for securing said shearing element in said arm member with said section projecting into the path of relative movement of the shearing member with said weakened portion adjacent to one end of said securing 130

means, the said companion members being held against relative movement by the shearing member contacting with said section and with a shoulder upon said arm member; and 5 means for controlling the movement of the broken off portion of the shearing element, that is separated from said element during the relative movement of said members.

5. In a connection mechanism, companion 10 members operatively connected with each other, and a shearing element secured in one member and projecting into the path of the other member so that when the same are moved in relation to each other, a portion 15 of said shearing element is broken off, and means connected with one of said members for guiding the movement of the broken off portion of said shearing element.

6. In a connection mechanism, companion 20 members operatively connected with each other, a shearing element secured in one member and projecting into the path of the other member so that when the same are moved in relation to each other a portion 25 of said shearing element is broken off, and means having an opening therethrough connected with one of said members for guiding the movement of the broken off portion of said shearing element.

30 7. In a connection mechanism, companion members operatively connected with each other, a shearing element secured in one member and projecting into the path of the other member so that when the same are moved in relation to each other a portion of 35 said shearing element is broken off, and laterally projecting means upon one side of one of said members for guiding the movement of the broken off portion of said shearing element, comprising a structure closed 40 on opposite sides with an outwardly inclined bottom face.

8. In a connection mechanism, companion 45 members operatively connected with each other, a shearing element secured in one member and projecting into the path of the other member so that when the same are moved in relation to each other a portion of said shearing element is broken off, laterally 50 projecting means upon one side of one of said members for guiding the movement of the broken off portion of said shearing element, comprising a structure closed on opposite sides with an outwardly inclined 55 bottom face, and a covering hood opposite said inclined face.

9. In mechanism of the character described, an arm member having a recess therein, a shearing element formed into sections 60 separated by weakened portions thereof; means for securing said shearing element in said recess so that one of said sections will project beyond the end thereof, a shearing member having a pivotal connection with said arm member, and a recess 65

therein which is substantially an extension of the recess in said arm member and into which projects that section of the shearing element projecting beyond the recess in said arm member, said shearing member being 70 formed with a laterally projecting portion with an opening therethrough forming an extension of the recess in said shearing member.

10. In mechanism of the character described, an arm member having a recess therein, a shearing element formed into sections separated by weakened portions thereof; means for securing said shearing element in said recess so that one of said sections 80 will project beyond the end thereof, a shearing member having a pivotal connection with said arm member, and a recess therein which is substantially an extension of the recess in said arm member and into which projects that section of the shearing element projecting beyond the recess in said arm member, said shearing member being 85 formed with a laterally projecting portion with an opening having one inclined face. 90

11. In mechanism of the character described, an arm member having a recess therein, a shearing element formed into sections separated by weakened portions thereof; means for securing said shearing element in said recess so that one of said sections will project beyond the end thereof, a shearing member having a pivotal connection with said arm member, and a recess therein which is substantially an extension 100 of the recess in said arm member and into which projects that section of the shearing element projecting beyond the recess in said arm member, said shearing member being formed with a laterally projecting portion 105 with an opening having one inclined face, and a covering hood at the end of said opening opposite said inclined face.

12. In mechanism of the character described, an arm member having a head 110 thereon with a recess therein and an angular face; a shearing element formed into sections separated by weakened portions thereof; means for securing the shearing element in said recess with one end thereof projecting; a shearing member having a pivotal connection with said arm member and a recess therein which is substantially 115 an extension of the recess in the head of said arm member and into which projects the projecting portion of the shearing element beyond the recess in said arm member, said shearing member being formed with a laterally projecting portion having an opening therethrough forming an extension 120 of the recess in the shearing member, which latter during the relative movement of said members is closed upon its outer end by the angular face upon the head of said arm member. 125

13. In a connection mechanism, companion members operatively connected with each other and a shearing element composed of a plurality of sections with a weakened portion therebetween, means for securing said shearing element in one of said members whereby a portion thereof projects into the path of relative movement of the other member, all of the parts being so designed and arranged that said shearing element is rigidly secured and a weakened portion thereof is in register with a face of the member with which it is connected and the other member has contact therewith at a point distant therefrom.
14. In a connection mechanism, companion members, one an arm member having a shoulder thereon, and the other a shearing member, operatively connected with each other, a shearing element having a section at one end separated from the remainder of said shearing element by a weakened portion; means for securing said shearing element in said arm member whereby said section projects into the path of relative movement of the shearing member with said weakened portion adjacent to one end of the securing means, said shearing member having contact with said section at a point beyond the said face of said arm member and when so engaged, the said members being held against relative movement by said shearing member having contact with said section and with the shoulder of said arm member.
15. In a connection mechanism, companion members comprising an arm member and a shearing member, operatively connected with each other, a shearing element having a section at one end separated from the remainder of said shearing element by a weakened portion; and means for securing said shearing element in said arm member all of said parts being so associated that said shearing member is held against relative movement by said shearing element

and a projecting portion of said arm member whereby said members and element operate as a unit under normal strains, but move relatively to each other under abnormal strains, at which time the projecting section of said shearing element will be broken off at said weakened portion and released from engagement with both of said members, the pressure of the shearing member thereon being applied at a point beyond its securing means.

16. In connection mechanism, companion members operatively connected with each other, a shearing element having contact with both of said members but secured in only one thereof, that portion of said shearing element in contact with the member to which it is not secured being broken off when said members move relatively to each other, the broken-off portion then being free from contact with either of said members.

17. In mechanism of the character described, an arm member having a head thereon with a recess therein and an angular face; a shearing element formed into sections; means for securing the shearing element in said recess with one end thereof projecting; a shearing member having a pivotal connection with said arm member and a recess therein which is substantially an extension of the recess in the head of said arm member and into which projects the projecting portion of the shearing element beyond the recess in said arm member, said shearing member being formed with a laterally projecting portion having an opening therethrough forming an extension of the recess in the shearing member, which latter during the relative movement of said members is closed upon its outer end by the angular face upon the head of said arm member.

In testimony whereof, I have hereunto affixed my signature.

RICHARD LESTER WILCOX.
